N. S. BEAN, OF MANCHESTER, NEW HAMPSHIRE.

Letters Patent No. 61,703, dated February 5, 1867.

IMPROVEMENT IN CARRIAGE-WHEELS.

The Schedule referred to in these Letters Patent and making part of the same.

TO ALL WHOM IT MAY CONCERN:

Be it known that I, N. S. BEAN, of Manchester, in the county of Hillsboro, and State of New Hampshire, have invented an Improvement in the Construction of Wheels having wooden spokes and metallic hubs; and I do hereby declare that the following, taken in connection with the drawings which accompany and form part of this specification, is a description of my invention sufficient to enable those skilled in the art to practise it.

In that class of wheels mostly used under heavy weights, in which the spokes are of wood set into mortises in metallic hubs, it is common to reduce the ends of the spokes entering the hubs into tenons, which, to keep them tight in the mortises formed in the hub, have but little taper, as it is found in practice that if the spokes are considerably tapered in the whole, or any material part of their length, where they enter the hub mortises, they work loose when the wheel tire stretches. Heretofore it has been the practice to form the hub tenons on the spokes with square shoulders, fitting upon the peripheral surface of the hub, but the effect of this in connection with metallic hubs is very often to split off the wood of the spoke where it extends beyond the side surfaces of the tenon. To retain the advantages of little or no taper in the length of the spoke tenons at their hub ends, and to prevent the wood of the spoke from splitting upward from the sides of the tenon, through being forced upon the periphery of a metal hub, is the object of my invention, which consists in making the shoulders or offsets; at the juncture of the tenon and spoke, with a bevelled formation instead of a square one, with a corresponding bevelled formation of the mouth or entrance of the hub mortise.

Figure 1 shows a sectional view of a portion of a metallic hub, with three wooden spokes set therein, in accordance with my improvement; and

Figure 2 shows a similar view of the ordinary way of setting wooden spokes in metallic hubs.

The metal around the axle cavity is marked *a*; the metal of the hub forming the sides of the mortises which are cored in the hub is marked *b*, while the line representing the peripheral surface of the hub is marked *c c*. The tenons on the wooden spokes are marked *d*, and the spokes themselves are marked *e*. In fig. 2, which illustrates the old construction, it will be seen that the shoulders, at the junction of the spokes *e* with the tenons *d*, are substantially square or at right angles with the central lines of the spokes, said shoulders resting directly on the peripheral surface of the hub. In fig. 1, which illustrates an embodiment of my improvement, it will be seen that the tenons blend into the spokes with bevelled or inclined surfaces, which correspond to depressions made in the material of the hub, so that the shoulders formed at the junction of the spokes with their tenons are inclined or bevelled instead of square or right-angular, and that they rest within the material of the hub instead of on its peripheral surface.

It will be evident that this peculiarity of construction greatly lessens the liability of the splitting of the wood of the spokes upward from the hub, and that all the advantages pertaining to substantial parallelism of the surfaces of the spoke tenons are preserved.

I claim the peculiarity of construction of the mortises of the metallic hub, and of the tenons of the wooden spokes, substantially as and for the purpose set forth.

N. S. BEAN.
